UNITED STATES PATENT OFFICE.

GEORGE W. DUVALL AND NORMAN H. BEEBE, OF DAVENPORT, IOWA, ASSIGNEES TO
MODERN BROOM MACHINERY COMPANY, OF DAVENPORT, IOWA, A CORPORATION
OF IOWA.

BROOM TRIMMER.

1,418,138.

Specification of Letters Patent. Patented May 30, 1922.

Application filed August 28, 1918. Serial No. 251,815.

To all whom it may concern:

Be it known that we, GEORGE W. DUVALL and NORMAN H. BEEBE, citizens of the United States, residing at Davenport, in the county 5 of Scott and State of Iowa, have invented certain new and useful Improvements in Broom Trimmers, of which the following is a specification.

This invention relates to machines de-10 signed to trim away the surplus fibre on the shoulder portion of metal clamp brooms.

In the accompanying drawings:

Figure 1 is a view in perspective of the complete machine;

15 Figure 2 shows in perspective the sliding knife head;

Figure 3 illustrates one of the knives detached from the head;

20 Figure 4 shows the appearance of a metal clamp broom after the shoulder has been trimmed by this machine;

Figure 5 is a perspective view of the broom holding form;

25 Figure 6 is a front elevation of the main frame.

The main frame 1 is mounted on the combined column and base 2. The upper portion of the main frame 1 forms the back and side guides within which the sliding knife 30 head 3 is free to move vertically. The outer guide plates 4 and 5 are attached to frame 1 by bolts *a* as shown. Cutters or knives 6 and 7 are attached to the head 3 by bolts *b* as shown in Fig. 1. The knives are slotted as 35 at *c* to receive the bolts. With this arrangement it is only necessary to loosen the bolts to remove the knives for sharpening.

Attention is called to the peculiar shape 40 of the knives. They are curved to conform to the outline of the broom-clamp 8 and also pointed to cut both ways.

The broom shown in Fig. 1 illustrates the appearance of the broom shoulder before 45 trimming. The broom shown in Fig. 4 shows the shoulder after trimming.

The point of the knife comes in contact with the broom corn or fibre at or near the side of the broom, and as the knife descends it cuts toward the handle or center of the 50 broom. With this arrangement, a shearing cut is produced. The cutting edge of the knife is beveled on the convex side of same.

The head 3 is connected to the foot treadle 9 by the bar 10 pivoted at *d*. The downward 55 movement of the treadle draws the head 3

together with the knives down, thus trimming the upper half of the broom shoulder. The broom is then turned over and the operation repeated, thus giving the shoulder the appearance of the one shown in Fig. 4. 60 As soon as the foot is removed from the treadle, the spring 11 draws the treadle, rod and head to their extreme upward position. A piece of yielding material 12, such as rubber or leather, is secured within the main 65 frame 1. This serves to bring the head 3 to a stop without making a disagreeable noise. The broom rests in the form 13, shown in Figures 1 and 5. As will be seen, the broom rests at three points. The two rear points 70 are provided with flanges, while the front bearing is semicircular in form to receive the round or handle portion of the clamps. As shown, the form is provided with two vertically extending lugs 15. These lugs are 75 grooved on the sides adjacent to the broom, as shown at 16. The outer edges of the knives operate within the grooves 16.

No. 14 is a shield, and serves to prevent the operator getting his fingers caught between the top end of head 3 and frame 1. 80

We claim:

1. The combination with a main frame having a form thereon upon which the broom is adapted to rest, the form flanked by 85 vertically extending lugs, said lugs having vertical grooves at their inner edges, of a head, knives adjustably connected therewith in position to trim the broom to conform substantially with the shape of the form, 90 with their outer edges in position to move vertically in the grooves of the lugs, and means for reciprocating the head.

2. The combination with a frame, a form thereon adapted to receive the broom to 95 be trimmed, the form flanked by upstanding lugs, of a reciprocating head, means for reciprocating the latter, pointed knives secured to the head so that the points of the knives come in contact with the broom corn 100 or fibres at or near the sides of the broom, and as the knives travel cut toward the center of the latter, thereby producing a shearing cut, and the outer edges of the knives traveling in contact with, and being laterally 105 supported by, the upstanding lugs.

3. The combination with a frame, a form thereon adapted to receive the broom to be trimmed, the form flanked by grooved up- 110 standing lugs, of a reciprocating head, means

for reciprocating the latter, pointed knives secured to the head so that the points of the knives come in contact with the broom corn or fibres at or near the sides of the broom, and, as the knives travel, cut toward the center of the latter, thereby producing a shearing cut, and the outer edges of the knives

traveling in contact with, and being laterally supported by, the grooves of the upstanding lugs.

In testimony whereof we affix our signatures.

GEORGE W. DUVALL.
NORMAN H. BEEBE.
